UNITED STATES PATENT OFFICE.

ALBERT BECK, OF CHICAGO, ILLINOIS, ASSIGNOR TO MCGILL METAL PRODUCTS COMPANY, A CORPORATION OF ILLINOIS.

SELECTIVE CHANGE MAKER.

Application filed July 20, 1921. Serial No. 486,105.

To all whom it may concern:

Be it known that I, ALBERT BECK, a citizen of the United States, and a resident of the city of Chicago, in the county of Cook and State of Illinois, have invented certain new and useful Improvements in a Selective Change Maker; and I do hereby declare that the following is a full, clear, and exact description of the same, reference being had to the accompanying drawings and to the numerals of reference marked thereon, which form a part of this specification.

This invention relates more particularly to an improved type of a selective change maker wherein a plurality of coin tubes are provided for holding coins of different denominations, each of said tubes having associated with the lower end thereof a lever-actuated spring-controlled bell-crank having a spring-controlled ejector supported on one end thereof for the purpose of ejecting a coin from the tube and causing said coin to move rearwardly into discharge position as a member preventing premature discharge of a coin and pivoted on the other end of the bell-crank is retracted to allow the coin to slide into a discharge chute.

It is an object of this invention to provide a selective change maker wherein a lever is provided for the purpose of actuating a spring-controlled bell-crank having pivotally mounted on the ends thereof coin control members between which a coin is normally positioned to permit ejection thereof.

It is also an object of this invention to provide a change maker wherein a coin in a coin tube is normally positioned between oppositely disposed control members, one of which normally acts to retain the coin in place until the ejecting member is actuated by a lever controlled pivoted means which simultaneously retracts the retaining member as it advances the ejecting member to cause discharge of the coin.

Another object of the invention is to provide a change maker having means on a coin retaining member for preventing a coin improperly deposited into a coin tube from dropping through a coin tube base slot when a coin ejector is in normal position.

It is a further object of the invention to provide a change maker wherein a lever is adapted to move a cam member forming a part thereof into engagement with a control

bell-crank to operate the same to simultaneously cause retraction of a coin retaining member on said bell-crank as a coin ejecting means also on said bell-crank is advanced to discharge the lowermost coin or coins from a stack of coins in a coin tube. 55

It is furthermore an object of this invention to construct a change maker having cam operated means for retracting a coin retaining mechanism as a coin ejecting mechanism is advanced to eject a coin. 60

It is an important object of this invention to provide a change maker of simple and effective construction adapted to be conveniently and positively operated to cause spring and roller controlled coin ejecting mechanisms to be advanced whereby a selected number of coins of selected denominations are adapted to be discharged from coin tubes into a delivery cup at the outer end of a discharge chute simultaneously with the retraction of coin retaining mechanisms operable by the same means actuating the coin ejecting mechanisms. 65

Other and further important objects of this invention will be apparent from the disclosures in the specification and drawings. 70

The invention (in a preferred form) is illustrated in the drawings and hereinafter more fully described.

On the drawings:

Figure 1 is a front elevation, partly broken away, of a selective change maker embodying the principles of this invention. 85

Figure 2 is an enlarged vertical section taken on line 2—2 of Figure 1.

Figure 3 is a reduced fragmentary detail section taken on line 3—3 of Figure 2. 90

Figure 4 is a sectional view taken on line 4—4 of Figure 2.

Figure 5 is a section taken on line 5—5 of Figure 2. 95

Figure 6 is a fragmentary detail view of one of the bell-cranks taken on line 6—6 of Figure 2.

Figure 7 is a fragmentary detail taken on line 7—7 of Figure 6. 100

Figure 8 is an enlarged detail section through the discharge end of the discharge chute taken on line 8—8 of Figure 5.

Figure 9 is an enlarged fragmentary detail taken on line 9—9 of Figure 1 showing coin retaining and ejecting mechanisms in normal position. 105

Figure 10 is a similar view showing the coin retaining and ejecting mechanisms at the end of the discharge position.

Figure 11 is a detail section similar to 5 that shown in Figure 10 showing the ejector depressed by the stack of coins and ready to be returned to normal position.

Figure 12 is a rear view of the lower end of one of the coin tubes.

10 Figure 13 is a fragmentary detail section taken on line 13-13 of Figure 6.

As shown on the drawings:

The selective change maker comprises a pedestal or base 1 having rigidly secured 15 thereon a casing 2. Fastened to the front inclined wall 3 of the casing 2 are a plurality of headed pins or bolts 4 for removably supporting a coin holding unit in position. The coin holding unit embraces a 20 pair of parallel cross-bars 5 having notches 6 in the lower edges to engage over the pins 4. Integrally formed on the cross bars 5 are a plurality of studs or projections 7. Rigidly secured to the studs 7 are a plurality 25 of parallel coin tubes 8 of different sizes for holding stacks of coins 9 of different denominations. Each coin tube 8 has rigidly secured on the lower portion thereof of a collar 10 having a discharge coin guide 30 or mouth piece 11 formed thereon to close the bottom thereof.

The coin tube mouth pieces 11 are positioned above an inclined coin discharge apron or plate 12 having a plurality of parallel slots 13 therein. The coin discharge apron 12 forms a part of a coin discharge chute 14 which is mounted within the lower rear portion of the casing 2. Both of the side walls of the casing 2 have outlet openings 15 therein. One of the openings 15 is closed by means of a plate or door 16 slideable in guide channels 17 formed on the casing side walls, as illustrated in Figures 4 and 5. The lower end of the discharge chute 14 leads to the opening 15 in the other casing side wall and connects up with an exterior delivery chute or trough 18, the end of which has a discharge opening 19 in the bottom thereof to permit coins to be deposited in a coin cup 20 positioned below the end of said delivery chute 18. The two openings 15 are provided in the casing side walls to permit either a right hand or a left hand coin delivery chute to be provided 55 with the machine.

The lower ends of the coin tubes are positioned to permit the base members 10-11 thereon to engage or seat in an inclined table casting or plate 21 provided with recesses or openings 22. The bottom of each tube base member 10-11 is provided with a slot 23, the rear end of which opens into a coin outlet opening 24. Secured against the bottom of the table casting 21 and beneath 60 the coin tube base members 10-11 is an

ejector guide plate 25 having ejector guide slots 26 therein registering with the coin tube guide slots 23 and with the openings 22 in the plate 21. The guide plate 25 is also cut away at the rear margin to afford coin outlet openings 27 which register with the openings 24 in the coin tube base members 10-11.

Each coin tube is provided with a coin ejecting mechanism the operation of which is best illustrated in Figures 2, 9, 10 and 11. Since the principle of operation and the construction of each of the various ejecting mechanisms is the same, only one ejecting mechanism will be described.

Pivotedly mounted on a rod or pin 28 within the casing 2 is the upper end of an arm 29 having an inwardly directed finger or projection 30 integrally formed intermediate the ends thereof. Also integrally formed on the lower inner edge of the arm 29 is a cam 31. A lever 32 is integrally formed at right angles to the lower front edge of the arm 29 and projects outwardly through a vertical slot 33 provided for the purpose in the lower front wall of the casing 2. A key or button 34 is secured on the outer end of the lever 32 and is provided with a number plate to designate the denomination of the coins 9 in a respective coin tube 8. Provided on the upper surface of the base 1 is a pair of spaced lugs 35 for supporting a pin or rod 36. Pivoted on the pin 36 between the lugs 35 is the bight portion of a bell-crank embracing an upwardly directed long arm 37 and a rearwardly directed short arm 38. The long bell-crank arm 37 is provided with a longitudinal slot 39, Fig. 6 through which the lever finger 30 and the cam 31 project. The inclined surface of the cam 31 is in contact with a roller 40 rotatably mounted between side flanges of the long bell-crank arm. Engaged around the pin 36 are a pair of springs 41, one end of each spring resting on the base 1 while the other end bears against the long bell-crank arm 37, as illustrated in Figure 7. The springs 41 act to return and hold the bell-crank 37-38 and the lever 32 in their normal positions.

Pivoted on the end of the short bell-crank arm 38 is the lower end of a coin retaining arm 42 which projects upwardly between adjustable slotted guide plates 43 and 44. The guide plates 43 and 44 are supported longitudinally of the casing 2 upon uprights 45 secured upon the machine base 1. As shown in Figure 4, the plate 43 is provided with transverse end slots 46 through which set screws 47 project and thread into the upper ends of the uprights 45. The slots 46 in the plate 43 permit said plate to be adjusted on said uprights. The guide plate 44 is provided with transverse slots 48 through which set screws 49 project and

- thread into the guide plate 43. The guide plate 44 is adjustable on the guide plate 43. The upper end of the coin retaining arm 42 is tapered and normally projects upwardly 5 through the slot 13 in the coin discharge apron 12 to the rear of the coin discharge opening 24-27 to prevent the lowermost coin or coins in the coin tube from prematurely sliding rearwardly out of the tube 10 and into the discharge chute 14. Integral- 75 ly formed near the upper end of the coin retaining arm 42 is an upwardly and forwardly inclined finger or stop 50 which projects beneath the registering guide slots 15 23-26 to prevent coins tipped on edge in the coin tube 8 from falling through said registering slots 23-26 into the casing 2.
- Supported in the upper head end of the long bell-crank arm 37 is a pin 51 on which 20 is pivotally engaged the arms 52 of an ejecting member. The ejecting member arms 52 are integrally connected by a cross-piece 53 having a notched upwardly projecting ejector tip 54 integrally formed thereon. To 25 hold the ejector projected upwardly with the ejecting tip or nose 54 projecting through the registering guide slots 23-26, a spring 55 is coiled around the pin 51. One 30 end of the spring 55 is engaged under one of the ejector arms 52 while the other end of the spring 55 bears against a flange 56 struck inwardly from the upper end of the long bell-crank arm 37, as illustrated in Figure 13. Rotatably mounted between the ejector 35 arms 52 is a guide roller 57 which in normal position is adapted to run on the under surface of the table guide plate 25 to limit the movement of the ejector tip 54 through the guide slots 23-26.
- 40 The ejector keys 34 are numbered "1", "2", "5", "10", "25" and "50" to indicate the denomination of the coins in the various coin tubes 8. The first and second tubes are for pennies, the third tube for nickels, the 45 fourth tube for dimes, the fifth tube for quarters, and the last tube for half dollars. The second key is numbered "2" to indicate that two pennies can be ejected by one operation of the key "2". The operation 50 of any of the other keys will result in the ejection of a single coin only of the required denomination from the respective coin tube.
- The operation is as follows:
- 55 Coins of different denominations such as pennies, nickels, dimes, quarters and half dollars are manually deposited in the respective coin tubes in stacks with the lowermost coin in each stack resting on the inner surface of the slotted bottom plate of the 60 tube base member 10-11 in the position illustrated in Figure 9.
- If, when coins are deposited in a coin tube, the lowermost coin should turn edgewise and project into the registering guide slots 65 23-26, said coin would not be permitted to slide through said guide slots into the casing 2, but would be stopped by the stop or finger 50 which normally is positioned with the upper end contacting the plate 25 below the guide slot 26. The coin or coins which 70 have been upturned may then be removed or set flat within the coin tube in stacked order ready to be ejected.
- In case there was only one or a very few coins in a tube and the lower coin started 75 to slide rearwardly by gravity toward discharge position, said coin would not be permitted to fall upon the discharge apron 12 in view of the fact that the upper end of the retaining arm 42 normally is held projected 80 upwardly through the slot 13 of the apron 12 across the end of the coin tube outlet or mouth 11, thereby holding said coin in the bottom of the tube against accidental discharge.
- 85 The control spring 41 acts to hold the bell-crank 37-38 and the actuating lever 32 in their normal positions, as illustrated in Figure 2. When the bell-crank is in normal position the coin retaining arm 42 is in the projected position shown in Figure 9, while the ejector control spring 55 acts to hold the ejector tip 54 projected upwardly through the guide slot 26 and into the table guide slot 22. The ejector roller 57 tracks on the under surface of the guide plate 25 to facilitate movement of the ejector and also serves as a stop to prevent the ejector tip 54 from projecting upwardly too far to engage 90 against the edge of more than one coin. The ejector in the case of the second coin tube from the left side of the machine is adjusted to permit the same to engage the two lower coins instead of only the lowermost coin as is the case for the remaining tubes.
- 100 105 With the ejector in normal position, as shown in Figures 2 and 9, the lowermost coin in a coin stack may be positively ejected by depressing the respective button or key 34 thereby forcing the lever 32 to swing 110 downwardly about the pivot point 28. With the above movement of the lever 32 the cam 31 is forced against the bell-crank roller 40. The bell-crank long arm 37 is thus tipped inwardly or rearwardly as the short bell-crank arm 38 is swung downwardly. As the lever 32 is pushed downwardly the projection 30 swings upwardly to act as a stop to limit the rearward throw of the bell-crank. With the rearward movement of 115 the bell-crank arm 37 against the action of the springs 41 the ejector is also forced inwardly with the ejector tip 54 sliding in the guide slots 23-26 to contact the lowermost coin 9 and slide the same rearwardly from underneath the stack of coins into 120 discharge position. With the throw of the bell-crank the retaining arm 42 on the short bell crank arm 38 is simultaneously retracted from the position shown in Figure 9 to the 125 130

position illustrated in Figure 10 out of the path of the coin being ejected. When the front edge of the coin reaches the cutout or outlet opening 24-27 the coin is permitted 5 to drop through the mouth of the coin tube base member 10-11 upon the discharge apron 12. The apron 12 is inclined to permit the ejected coin to slide downwardly by gravity into the chute 14. From the chute 10 14 the coin passes out of the casing into the exterior chute 18 and finally drops through the opening 19 into the coin cup 20.

Simultaneous with the discharge of a coin the stack of coins tends to drop in the coin 15 tube and rest upon and depress the ejector tip 54, as illustrated in Figure 11, compressing the spring 55. As soon as the lever is released the main control springs 41 act 20 automatically to return the bell-crank to normal position. The ejector is thus retracted or pulled outwardly while the retaining arm 42 is moved upwardly through the apron slot 13 behind the lower open end 25 of the coin tube. As soon as the ejector tip 54 clears the outer or front portion of the lowermost coin in the coin stack the ejector control spring 55 acts automatically to swing the ejector upwardly into normal position, as shown in Figure 9, in place to permit 30 ejection of the next coin upon the next operation of the lever 32.

Any combination of change may be rapidly made by simultaneously depressing a selective number of the ejecting keys 34. The 35 various ejector mechanisms may be operated independently or collectively as desired.

The coin tubes 8 are all secured to the cross bars 5 to form a unit which may be easily removed from the machine by simply 40 lifting the unit to disengage the notch bars from the supporting pins 4 secured on the upper front casing plate 3.

I am aware that numerous details of construction may be varied through a wide range 45 without departing from the principles of this invention, and I therefore do not purpose limiting the patent granted otherwise than necessitated by the prior art.

I claim as my invention:

50 1. A change maker comprising a coin-holding tube, an ejector co-acting with said tube, a pivoted key lever, a bell-crank positioned to be operated thereby, said ejector mounted on one end of said bell-crank to contact 55 with a coin in said tube, and a coin retaining member supported on the other end of the bell-crank in back of said coin to hold the same in place against accidental discharge.

2. A selective change maker comprising a 60 coin holding tube and an ejector mechanism, said ejector mechanism embracing a bell-crank, a coin retaining member on one arm thereof, and an ejecting means on the other arm.

65 3. A change maker comprising a coin

holding tube and an ejector mechanism associated therewith, said ejector mechanism embracing a pivoted bell-crank, a coin retaining member pivoted on one arm of the bell-crank, an ejector on the other bell-crank 70 arm, and a pivoted key lever for operating said bell-crank.

4. A change maker comprising a coin holding tube and an ejector mechanism associated therewith, said ejector mechanism 75 comprising a pivoted spring controlled bell-crank, a coin retaining member pivoted on one arm of the bell-crank, an ejector on the other bell-crank arm, rotatable means on 80 said bell crank, a cam contacting with said rotatable means, and a key lever for actuating said cam to cause operation of the bell-crank.

5. A change maker comprising a coin tube, a spring controlled pivoted bell-crank, 85 a retaining member pivoted on one arm of the bell-crank, a coin stop integrally formed on said retaining member normally projecting beneath the coin tube, guide means for said retaining arm, a spring controlled ejector pivotally mounted on the other bell-crank arm, a roller on said ejector, a roller 90 on said bell-crank, a pivoted arm, a cam formed thereon and contacting with said bell-crank roller, and a control lever integral 95 with said pivoted arm.

6. A change maker comprising a slotted coin tube, a slotted spring controlled pivoted bell-crank, a cam retaining member pivoted on one arm of the bell-crank, a coin 100 stop integrally formed on said retaining member, adjustable guides for said retaining member, an ejector pivoted on the other arm of the bell-crank, a spring connected therewith for holding the ejector projected through the coin tube slot, a roller on said 105 ejector for limiting the upward movement of the ejector, a roller on the bell-crank, a pivoted arm, a projection thereon projecting through one of the bell-crank slots, a cam 110 formed on said pivoted arm and projecting through another of the bell-crank slots to engage the bell-crank roller, a lever integral with said pivoted arm, and a key on 115 said lever.

7. A change maker comprising a coin tube and an ejector, said ejector comprising a key lever, a bell-crank to be actuated thereby, and coin ejecting and retaining mechanisms mounted on different ends of said bell-crank.

8. In a change maker the combination with a spring controlled bell-crank, a retaining means supported on one arm thereof, and a coin ejecting means mounted on the other arm of said bell-crank.

9. In a change maker the combination with a coin holder, of a bell-crank, a coin retaining member on one arm of the bell-crank, a coin ejecting means on the other 130

arm of the bell-crank, and cam means for actuating said bell-crank to retract the retaining member as the ejecting means is advanced.

5 10. In a change maker the combination with a slotted coin holder, of a coin retaining member normally positioned to hold coins against premature discharge, and a stop on said retaining member to hold tipped 10 coins in said coin holder from dropping through the slot thereof.

11. In a change maker the combination with a slotted coin holder, of a coin retaining member normally positioned to hold 15 coins against premature discharge, a stop on said retaining member to prevent tipped coins in said coin holder from dropping through the slot thereof, and means for retracting said retaining member and said 20 stop.

12. In a change maker the combination with a coin tube, of a spring controlled slotted bell-crank, a spring controlled ejector pivotally supported in one end of the bell 25 crank, a roller in the bell-crank, a pivoted member, and a cam formed thereon projecting through the slotted lever to engage said roller to cause discharge of a coin from the tube when the pivoted member is operated.

30 13. A change maker comprising a base, a casing secured thereon, a coin tube unit on said casing, a discharge chute in said casing, a slotted apron connected therewith and projecting underneath the coin tube unit, coin 35 retaining members projecting upwardly through said slotted apron behind the coins in the coin tube unit, a plurality of ejectors, and means adapted to be operated to cause simultaneous retraction of the retaining 40 members and operation of the ejectors to discharge coins from the coin tube unit upon said apron for discharge through said chute.

14. A change maker comprising a base, a casing mounted thereon, a coin tube unit on 45 said casing, a discharge chute in said casing, a slotted apron integral therewith and projecting underneath the coin tube unit, uprights on said base projecting into said casing, bell-cranks within said casing supported on said base, coin retaining members pivoted on one end of the bell-cranks and normally projecting through said slotted 50 apron, a slotted plate adjustably mounted on

said uprights, a second plate adjustably engaged on said slotted plate, said plates serving as guides for said retaining members, ejectors supported on the other ends of said bell-cranks and projecting into said coin tube unit, rollers in said bell-cranks, and a plurality of cam levers pivotally supported in said casing and engaging said rollers, said levers adapted to be operated independently and selectively to actuate the bell-cranks to cause simultaneous retraction of said retaining members and operation of said ejectors to eject coins from said coin unit into said discharge chute.

15. In a change maker the combination with a coin tube, of a slotted bell-crank, springs holding the bell-crank in retracted 70 position, a roller in said bell-crank, a pivoted arm, a projection thereon projecting through said slotted bell-crank, a cam integral with said arm and projecting through said slotted bell-crank to engage said roller, coin control members mounted on both arms of the bell-crank, and a key lever integral with said pivoted arm adapted to be operated to cause simultaneous operation of said coin control members to eject coins from the coin tube, 75 said projection adapted to act as a stop for said bell-crank when actuated by the key lever.

16. In a change maker the combination with a coin holder, of coin ejecting means 80 associated therewith, and a member pivoted thereon adapted to hold tipped coins in said coin holder from dropping therefrom.

17. A change maker comprising a casing, coin ejecting means therein, a plurality of 85 coin tubes on said casing, slotted base members secured on the lower ends of said coin tubes into which said ejecting means project, means for operating the ejecting means to cause discharge of coins from said tubes, and 90 mouth pieces integrally formed on said coin tube base members through which the discharged coins are ejected.

In testimony whereof I have hereunto subscribed my name in the presence of two 100 subscribing witnesses.

ALBERT BECK.
